CURVED EDGE SCISSORS

William Bell, Brooklyn, N. Y.

Application July 21, 1944, Serial No. 545,966

5 Claims.

(Cl. 30—229)

This invention relates to new and useful improvements in scissors for cutting round corners on objects such as photographs or the like.

More specifically, the invention proposes the construction of a scissors characterized by having a curved portion for rounding, by cutting, the corners of photographs or the like.

Still further, it is proposed to provide a scissors as aforesaid having adjustable guides for guiding the photograph properly to the cutting edges of the scissors.

A further object of the invention is to provide a scissors as aforesaid having a receptacle for catching the portion cut from the photograph.

Another object is to provide a scissors as aforesaid having removable cutting blades.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a scissors constructed in accordance with this invention, in partly open position.

Fig. 2 is an enlarged perspective view of a cutting blade of the scissors of Fig. 1.

Fig. 3 is a plan view of the member of the scissors of Fig. 1 having the receptacle.

The scissors, according to this invention, comprises two members 10 and 11 pivotally connected together by a screw 12, and each having a handle 13. Member 10 is similar to the corresponding member of an ordinary pair of household scissors except that only a portion thereof is adapted to cut, this portion being a curved portion 14 having a removably cutting blade 26. Portion 14 may have a continuation point 14* and blade 26 may have a sharp edge for cutting similar to the sharp edge of ordinary household scissors, or it may have a thick cutting edge with a sharp corner similar to table-type paper trimmers. In using the scissors, member 10 will be the upper member descending down on the photograph to cut the corner thereof.

The member 11 has a hollow portion 15 having a removable cutting blade 26' complementary to the cutting edge of blade 26 and in cutting the corner of the photograph, the corner will be disposed on the portion 15 and overlap the blade 26' so that it will be cut off when the portion 14 passes the blade 26'. Thus portion

blades 26 and 26' coact to cut the corner of the photograph after the fashion of a conventional pair of scissors or a conventional table-type paper trimmer. The top of the portion 15 adjacent the blade 26' is cut out providing an edge 31.

A receptacle 17 is formed integrally with portion 15 and is box-shaped, being open adjacent the blade 26' so that clippings cut from the photograph will drop into the receptacle and will not fly around. Receptacle 17 extends completely under the portion 15 and therebeyond as is clearly shown in Fig. 2. While the portion 15 and receptacle have been shown and described as integral, they may be made separately and connected together by screws if desired.

The top wall 18 of the portion 15 forms a support for the photograph. Two guides 19 are fixedly or removably secured to the wall 18 for positioning the corner of the photograph to be cut. Normally these guides will be disposed at right angles to each other. However, each guide, which is rectangular in shape, is provided with a slot 20 through which extends a screw 21 by means of which the guides 19 may be moved to change the open space between the guides for accommodating different types of photographs. Also the guides may be completely removed when desired to accommodate very large photographs from which a large corner piece is to be cut.

The receptacle 17 opens through the back face of the member 11 and is closed by a door 22 connected to the back wall of the portion 15 by hinges 23. A spring 24 normally holds the door closed. Instead of hinges 23 the door 22 may be held in position by screws, clips or by any other holding means.

40 The removable cutting blades are provided so that curved corners of different radii may be cut and so that dull cutting blades may be removed for replacement or sharpening.

Both members 10 and 11 are provided with removable cutting blades 26 and 26' respectively, as aforesaid, one being shown in Fig. 10. Blades 26 and 26' each have a curved cutting portion 27 and two wings 28 in each of which is a slot 29 for receiving a screw 30 securing the blades 26 and 26' to the members 10 and 11. Screws 30 are countersunk in the blades so that they do not interfere with the flush surface of the wings 28. Member 10 is formed offset at the portions engaged by the wings 28 so that the wings do not interfere with the scissor action of the members

10 and 11. The same is true of the connection of the blade 26' with the member 11.

It will be understood that whatever size blade 26 is attached to member 10, a complementary blade 26' which will properly coat therewith is attached to member 11. The receptacle of the scissors is of such a size that it will contain several interfitted members 26 and 26' which may be stored in the receptacle, if desired, when the scissors is not in use.

The operation of the scissors is as follows:

When it is desired to cut off the square corner of a photograph, either positive or negative, or a pile of photographs, or some other paper object or object of some material which may be cut by the scissors, the object is placed between the guides 19, which line up the object so that the corner will be cut properly, and the two members of the scissors are then brought together, blade 26 coacting with blade 26' to cut the corners of the object, the corners dropping into the receptacle 17, from which they may be removed through the door 22.

While I have illustrated and described the preferred embodiment of my invention, it is to be understood that I do not limit myself to the precise construction herein disclosed and the right is reserved to all changes and modification coming within the scope of the invention as defined in the appended claims.

Having thus described my invention, what I claim as new and desire to secure by United States Letters Patent is:

1. A scissors for cutting the corner of an object to round it, comprising two members pivotally secured together, each provided with a handle and a supporting portion, a cutting blade secured by screws to each of said supporting portions, each of said blades having a curved portion and two slotted wings at opposite sides thereof, said screws being disposed in said slots, said curved portions being complementary to each other, one of said members being provided with a pair of adjustable guides removably secured to its said supporting portion adjacent its said cutting blade for guiding said corner to said cutting blades, a receptacle on one supporting portion beneath its said cutting blade having an opening for catching a portion cut from said corner and another opening, and a door openably secured to said receptacle over said other opening for removal of said cut portions.

2. A scissors for cutting the corner of an object to round it, comprising two members pivotally

secured together, each provided with a handle and a supporting portion, and a cutting blade secured by screws to each of said supporting portions, said blades being complementary, each of said blades having a curved portion and two slotted wings at opposite sides thereof, said screws being disposed in said slots, said curved portions being complementary to each other.

3. A scissors for cutting the corner of an object to round it, comprising two members pivotally secured together, each provided with a handle and a supporting portion, and a cutting blade secured by screws to each of said supporting portions, said blades being complementary, each of said blades having a curved portion and two slotted wings at opposite sides thereof, said screws being disposed in said slots, said curved portions being complementary to each other, each of said supporting portions being curved opposite its correlated blade curved portion and spaced therefrom providing room for assembling other blades with larger curved portions therewith.

4. A scissors for cutting the corner of an object to round it, comprising two members pivotally secured together, each provided with a handle and a supporting portion, and a cutting blade secured by screws to each of said supporting portions, said blades being complementary, each of said blades having a curved portion and two slotted wings at opposite sides thereof, said screws being disposed in said slots, said curved portions being complementary to each other, one of said members being provided with a pair of adjustable guides removably secured to its said supporting portion adjacent its said cutting blade for guiding said corner to said cutting blades.

5. A scissors for cutting the corner of an object to round it, comprising two members pivotally secured together, each provided with a handle and a supporting portion, a cutting blade secured by screws to each of said supporting portions, said blades being complementary each of said blades having a curved portion and two slotted wings at opposite sides thereof, said screws being disposed in said slots, said curved portions being complementary to each other, a receptacle beneath its said cutting blade having an opening for catching a portion cut from said corner and another opening, and a door openably secured to said receptacle over said other opening for removal of said cut portions.

WILLIAM BELL.
